(57) **CLAIM**

We claim the ornamental design for an enclosure design panel, as shown and described.

DESCRIPTION

FIG. 1 is a front left top side perspective view of an enclosure design panel comprised of a plurality of subunits.

FIG. 2 is a front elevational view thereof.

FIG. 3 is a back elevational view thereof.

FIG. 4 is a left side elevational view thereof.

FIG. 5 is a right side elevational view thereof.

FIG. 6 is a top plan view thereof.

FIG. 7 is a bottom plan view thereof.

FIG. 8 is a close-up isometric view of one subunit of the enclosure design panel; and,

FIG. 9 is an expanded view of the subunit of the enclosure design panel.

The broken lines in the drawings illustrate portions of the enclosure design panel which form no part of the claimed design.
